UNITED STATES PATENT OFFICE.

MARTIN L. BEISTLE, OF SHIPPENSBURG, PENNSYLVANIA.

DESIGN FOR A CHRISTMAS-TREE FENCE.

46,308.

Specification for Design.

Patented Aug. 25, 1914.

Application filed June 27, 1914. Serial No. 847,763. Term of patent 7 years.

To all whom it may concern:

Be it known that I, MARTIN L. BEISTLE, a citizen of the United States of America, and a resident of Shippensburg, in the county of Cumberland and State of Pennsylvania, have invented a new, original, and ornamental Design for Christmas-Tree Fences, of which the following is a specification, reference being had to the accompanying drawing, forming a part thereof.

The drawing is an elevation of a Christmas tree fence showing my new design.

I claim:

The ornamental design for a Christmas tree fence, as shown.

MARTIN L. BEISTLE. [L. S.]
